CLAIM

The ornamental design for an armband identification passholder with a transparent front face, as shown and described.

DESCRIPTION

FIG. 1 is a front elevational view of an armband identification passholder with a transparent front face showing my new design.

FIG. 2 is a rear elevational view thereof.

FIG. 3 is a bottom plan view.

FIG. 4 is a top plan view.

FIG. 5 is a left side elevational view thereof.

FIG. 6 is an enlarged scale cross-sectional view taken along line 6—6 of FIG. 1.
